[57] ABSTRACT

Disclosed herein is a pulse generator for producing repetitive uni-directional pulses or single signal-initiated uni-directional pulses by use of pulse generation means, in which output pulses each having an extremely short rise time can be obtained by applying the output pulses of the pulse generation means to a step recovery diode to render the diode non-conductive during such pulses; while the step recovery diode is otherwise maintained conductive, in the absence of a pulse from the pulse generation means, by flowing a forward dc current therethrough.

PULSE GENERATOR FOR FAST RISE-TIME PULSES

This invention relates to a pulse generator for producing repetitive uni-directional pulses or single signal-initiated uni-directional pulses.

In the case of digital control techniques, digital communication techniques and/or digital measurement techniques etc., uni-directional pulses, each having a short and constant rise time, are desirable to perform as desired operation in a high-speed and precise manner. However, the rise time of each pulse generated from conventional pulse generators deviates usually in accordance with a change of the pulse duration, or the repetition frequency thereof. Moreover the rise time of a generated pulse is usually extended in a shaping network employed to eliminate "overshoot" or "sag (tilt)" of the generated pulse. Accordingly, it is very difficult to generate repetitive uni-directional pulses or single signal-initiated uni-directional pulses each having a stable and short rise time without overshoot or sag.

An object of this invention is to provide a pulse generator in which the above-mentioned defects of conventional generators have been eliminated and which generates repetitive uni-directional pulses, or single signal-initiated uni-directional pulses, each having a stable and short rise time.

The principle of this invention will be better understood from the following more detailed discussion taken in conjunction with the accompanying drawings, in which the same or equivalent parts are designated by the same reference numerals, characters and symbols, and in which:

FIG. 1 is a circuit diagram illustrating an embodiment of this invention for generating pulses of positive polarity;

FIGS. 2A and 2B are wave-form diagrams explanatory of the operation of the embodiment shown in FIG. 1;

FIG. 3 is a circuit diagram illustrating an embodiment of this invention for generating pulses of negative polarity;

FIG. 4 is a circuit diagram illustrating another embodiment of this invention for generating pulses of positive polarity;

FIG. 5 is a circuit diagram illustrating another embodiment of this invention for generating pulses of negative polarity;

FIG. 6 is a circuit diagram illustrating another embodiment of this invention for generating pulses of positive polarity;

FIGS. 7A and 7B are wave-form diagrams explanatory of the operation of the embodiment shown in FIG. 6;

FIG. 8 is a circuit diagram illustrating another embodiment of this invention for generating pulses of negative polarity;

FIG. 9 is a circuit diagram illustrating another embodiment of this invention for generating pulses of positive polarity; and

FIG. 10 is a circuit diagram illustrating another embodiment of this invention for generating pulses of negative polarity.

With reference to FIG. 1, an embodiment of this invention will be described. In this example, trigger pulses of positive polarity are applied through an input terminal 1 and a capacitor C_1 . Bleeder resistors R_1 and R_2 are connected in series between a negative terminal (-C) of a dc source and ground potential. The junction between the resistors R_1 and R_2 is connected, through a winding of a transformer T_1 , to the base of a transistor TR_1 to apply a bias voltage thereto. The transistor TR_1 , the transformer T_1 , a diode D_1 , a resistor R_3 (employed as a current limiter) and a capacitor C_2 , form a blocking oscillator. The output voltage of the blocking oscillator is derived from another winding of the transformer T_1 and amplified by a transistor TR_2 . A positive terminal (+B) and a negative terminal (-B) of a dc source are connected, directly, and through a series connection of a coil L_1 and a resistor R_6 , to the collector and the emitter of the transistor TR_2 respectively. Resistors R_4 and R_5 and a capacitor C_3 are employed as current-adjusting means of the transistor TR_2 . The potential of the collector of the transistor TR_2 is grounded through a capacitor C_5 with respect to the alternating-current component thereof. The emitter of the transistor TR_2 is connected to a shaping network comprising resistors R_7 , R_8 and R_9 and a capacitor C_4 . A step-recovery diode (i.e., snap-off diode or charge storage diode; hereinafter referred to as "S.R. diode") D_2 is connected across the output terminal of the shaping net-

work and ground. The anode of a high-speed switching diode D_3 is connected to the cathode of the S.R. diode D_2 , and the cathode of this diode D_3 is connected to the center conductor of a coaxial output connector 2. A reference resistor R_0 has a load impedance approximating 50 ohms.

When a positive trigger pulse is applied to the input terminal 1, the transistor TR_1 of the blocking oscillator is turned from the OFF-state to the ON-state. This ON-state of the transistor TR_1 continues during a time determined by values of the capacitor C_1 , the resistors R_1 , R_2 and R_3 , and the impedance of the winding of the transformer T_1 , and is thereafter turned to the OFF-state. In response to this change of state, a negative pulse is obtained at the collector of the transistor TR_1 . This pulse is applied, through a winding of the transformer T_1 , to the base-emitter path of the transistor TR_2 , so that the potential of the base of the transistor TR_2 becomes positive to cause the transistor TR_2 to be switched to its ON-state during the duration of this pulse. On the other hand, a direct current flows through the S.R. diode D_2 , the resistors R_9 and R_7 , the coil L_1 and the resistor R_6 to an negative terminal (-B). Accordingly, the S.R. diode D_2 assumes the ON-state during the non-conductive interval of the transistor TR_2 , and the potential of the cathode of the S.R. diode D_2 is maintained at a voltage of about -0.8 volts. In response to the above-mentioned change of state of the transistor TR_2 , a positive pulse v_1 is obtained at the emitter of the transistor TR_2 . The pulse rise time of this positive pulse v_1 is usually about 5 nano-seconds (5×10^{-9} seconds). This positive pulse v_1 is applied to the S.R. diode D_2 through the shaping network comprising the resistors R_7 , R_8 and R_9 and the capacitor C_4 .

When the positive pulse v_1 is applied to the S.R. diode D_2 , which diode has a dc current flowing therethrough in the forward direction, the direction of the dc current is at first turned to the backward direction of the S.R. diode D_2 without changing the conductive state thereof to the OFF-state. The S.R. diode D_2 then turns to the OFF-state after the expiration of the storage time t_{stu} of the S.R. diode D_2 , so that a positive pulse v_2 is obtained at the cathode of the S.R. diode D_2 at this time, as shown in FIG. 2A. The transition time t_t of the S.R. diode D_2 necessary to turn from the ON-state to the OFF-state is approximately 100 pico seconds (100×10^{-12} seconds). This positive pulse v_2 is applied to the coaxial output connector 2 through the high-speed switching diode D_3 . The fluctuated low voltage region of the positive pulse v_2 is cut by the high-speed diode D_3 , so that a square pulse v_3 having a pulse rise time approximating 100 pico-seconds is obtained at the coaxial output connector 2 as shown in FIG. 2B. This square pulse v_3 rises fast from a potential level of substantially zero.

The storage time t_{stu} of the S.R. diode D_2 is variable in accordance with changes of values of the resistors R_9 , R_7 and R_6 and the voltage of the negative terminal (-B), so as to vary the forward dc current of the S.R. diode D_2 . This storage time t_{stu} is determined so as to be equal to or longer than the pulse rise time t_o of the pulse v_2 . The amplitude of the output square pulse v_3 is substantially equal to $r_o/(r_7 + r_9 + r_6)$ times the voltage of the positive terminal (+B); where the values r_o , r_7 and r_9 are respectively the resistances of the resistors R_9 , R_7 and R_6 . Accordingly, the output square pulse having a relatively large amplitude can be obtained at the coaxial output connector 2.

The shaping network, comprising two series connected resistors R_7 and R_9 , and a series connected capacitor C_4 and resistor R_8 connected in parallel with one of the resistors R_7 and R_9 serves as a current limiter for the transistor TR_2 and the high-speed switching diode D_3 in case a short circuit of the coaxial output connector 2, in addition to having the above mentioned pulse-form shaping function. Moreover, since the emitter of the pulse-amplifying transistor TR_2 is directly coupled with the diodes D_2 and D_3 , through a transfer impedance transmissible of a direct current, the storage time t_{stu} of the transistor TR_2 and the pulse rise time of the output square pulse v_3 are stably maintained even if the duration and/or the repetition frequency of the output square pulse v_3 are/is varied.

In this example, a blocking oscillator synchronized with the external trigger pulses is employed. Of course, a blocking oscillator of non-synchronous type or another pulse generation means, such as multivibrator or a pulse generator using other active elements, may also be employed. Moreover, if desirable, the pulse amplifier using the transistor TR_2 may be eliminated, so that the output of the pulse generation means (e.g., the blocking oscillator) is applied to the S.R. diode D_2 through the shaping network.

If negative output pulses are desirable, the embodiment shown in FIG. 1 can be modified as shown in FIG. 3. In this embodiment, the output of the transistor TR_2 is derived from the collector thereof, and the forward directions of the diodes D_2 and D_3 are directed in the reversed directions to those shown in FIG. 1. Since the construction and operation of this embodiment can be understood on reference to those shown in FIG. 1, details are omitted.

With reference to FIG. 4, another embodiment of this invention will be described for generating output pulses each having a relatively high amplitude. In this embodiment, the anode of a switching diode D_4 is connected to the junction of the cathode of S.R. diode D_2 , the anode of the switching diode D_3 and the resistor R_9 ; and the cathode of the switching diode D_4 is connected to a positive terminal (+E) of a dc source. A capacitor C_6 is employed to ground an alternating current passing through the diode D_4 . Other elements are arranged in the same connection as the embodiment shown in FIG. 1.

In this embodiment, if it is assumed that the voltage of the positive terminal (+B) is 40 volts, a total resistance of the resistors R_7 and R_9 is 50 ohms and the resistance r_o of the load resistor R_o terminating the coaxial output connector 2 is 50 ohms, a square pulse of 20 volts will be obtained at the cathode of the S.R. diode D_2 and at the coaxial output connector in a case where the forward resistances of the transistor TR_2 and of the diode D_3 are negligible. In this case, if it is assumed that the maximum allowable inverse voltage (inverse breakdown voltage) V_R of the S.R. diode D_2 is 20 volts, the diode D_2 can withstand the voltage (20 volts) of the output pulse. However, if the load resistor R_o connected to the coaxial output connector 2 is removed, in a case where the diode D_4 is not used, an inverse voltage of 40 volts will be applied across the S.R. diode D_2 , with the result that S.R. diode D_2 will be broken down since the maximum inverse allowable voltage V_R (25 volts) is less than the applied inverse voltage (40 volts). To avoid this breakdown, a dc voltage of 22 volts is applied to the cathode of the diode D_4 from the positive terminal (+E). Accordingly, if it is assumed that the voltage drop of the diode D_4 in the forward direction is equal to a voltage 0.8 volts, the terminal voltage of the S.R. diode D_2 is limited to the voltage 22.8 volts since the diode D_4 switches to the ON-state when the voltage of the cathode of the S.R. diode D_2 exceeds the voltage 22.8 volts. As mentioned above, even if the coaxial output connector 2 becomes an open circuit without the load resistance (R_o), the S.R. diode will not be broken down since the applied voltage of 22.8 volts is less than the breakdown voltage V_R (25 volts). In the case where the load resistance of 50 ohms is connected to the coaxial output connector 2, the diode D_4 assumes the OFF-state since the maximum voltage of the output pulse is equal to 20 volts. If the voltage applied from the positive terminal (+E) is determined at an appropriate value, the S.R. diode D_2 will not be broken down in the case of the open circuit of the coaxial output connector 2, even if the voltage of the output pulse obtained at the coaxial output connector 2 with the load resistance of 50 ohms approximates the breakdown voltage V_R (25 volts). In a case where the diode D_4 , the capacitor C_6 and the positive dc source connected to the positive terminal (+E) are not used, the voltage of the positive terminal (+B) must be less than the breakdown voltage V_R (25 volts) to avoid the breakdown of the S.R. diode D_2 at the open circuit of the coaxial output connector 2. Accordingly, the maximum voltage of the output pulse obtained at the coaxial output connector 2 with the load resistance of 50 ohms will be less than a voltage 12.5 volts.

If negative output pulses are desirable, the embodiment shown in FIG. 4 can be modified as shown in FIG. 5 in accordance with the same modification condition as described with reference to the embodiments shown in FIGS. 1 and 3. Since this embodiment of FIG. 5 will be readily understood from the embodiments shown in FIGS. 3 and 4, details are omitted.

The inverse breakdown voltage of the S.R. diode D_2 decreases generally in accordance with the decrease of the rise time t_r . However, output pulses each having a very short rise time and a relatively large amplitude can be obtained by the embodiments shown in FIGS. 4 and 5.

With reference to FIG. 6, another embodiment of this invention, modified from the embodiment of FIG. 1 and suitable to improve further the wave form of the output pulse, will be described. In this embodiment, a distributed constant circuit 3 is inserted between the shaping circuit (comprising the capacitor C_4 and the resistors R_7 , R_8 and R_9) and the S.R. diode D_2 . Other elements are arranged in the same connection as the embodiment of FIG. 1.

In this embodiment, if the output pulse, obtained at the coaxial output connector 2 terminated with a load resistance, has a wave form v_{11} , shown in FIG. 7A, which is formed by a sharp rise part 4, and a gentle rise part 5 succeeding to the sharp rise part 4 and reaching a constant level part 6, this wave form v_{11} can be shaped as a wave form v_{12} by the shaping circuit.

In general, the shorter the rise time of the output pulse, the more overshoot or sag (tilt) 7 it will have, as shown in FIG. 7B. To eliminate this overshoot or sag including higher frequency components, the distributed constant circuit 3 is employed. The pulse rise time of the pulse obtained from the pulse amplifier (TR_2) may be usually about 5 nano-seconds. While the distributed constant circuit 3 does not substantially affect such a pulse, the output pulse reshaped so as to have a very short rise time by the S.R. diode D_2 is affected by the distributed constant circuit 3. Accordingly, the overshoot or sag 7 on the output pulse v_{13} can be eliminated or reduced by adjusting the characteristic impedance of the distributed constant circuit 3 at frequencies suitable to eliminate respective concavities and convexities. If the interval of the overshoot or sag is relatively long, the delay time of the distributed constant circuit 3 will be long.

A strip transmission line or a distributed constant line can be employed as the distributed constant circuit 3. For example, if a concavity occurs, on a wave shown in FIG. 7B, at a time delayed by t nano-seconds after the rise position 8, an exact position along the distributed constant circuit 3 corresponding to the concavity, can be readily detected. In other words, if a small metal rod contacts a portion of the distributed constant circuit 3, fluctuations occurring at a portion of the output pulse v_{13} corresponding to the contact portion can be observed on a display device, such as a cathode-ray oscilloscope, and the above detection will be easily performed. In general, the position of the concavity or convexity corresponds to a position on the distributed constant circuit 3 affecting a delay time $t/2$ measured from the diodes D_2 and D_3 . Accordingly, the concavity or the convexity can be eliminated by connecting a line having a length corresponding to the duration of the concavity or convexity to this detected position of the distributed constant circuit 3, or by connecting the line through a resistor to the detected position if the amplitude of the concavity is relatively small.

The distributed constant circuit 3 can serve further to make the pulse rise time of the output pulse shorter. That is, an output pulse having a shorter rise time has a great amount of higher harmonic frequencies of the fundamental frequency component of the output pulse, and, therefore, the characteristic impedance of the distributed constant circuit 3 is made higher for the higher harmonic frequencies, so that the greater part of the higher harmonic frequencies can reach the output coaxial connector 2. In this case, the characteristic impedance of a portion of the distributed constant circuit 3 corresponding

to the rise time or to a time, slightly longer than the rise time, is made higher. This is performed by the use of a smaller size line at this portion of the distributed constant circuit 3.

The above-mentioned merits cannot be obtained by inserting a distributed constant circuit between the S.R. diode D_2 and the coaxial output connector 2, since a short rise time of a pulse reshaped by the S.R. diode D_2 will be extended at the distributed constant circuit.

If negative output pulses are desirable, the embodiment shown in FIG. 6 can be modified as shown in FIG. 8 in accordance with the same modification condition as described with reference to the embodiments shown in FIGS. 1 and 3. Since this embodiment of FIG. 8 will be readily understood from the embodiments shown in FIGS. 3 and 6, details are omitted.

The above-mentioned embodiments shown in FIGS. 6 and 8 may be provided, respectively as shown in FIGS. 9 and 10, with the switching diode D_4 and a capacitor C_8 each connected to the positive terminal (+E) or the negative terminal (-E) of a dc source to improve the inverse breakdown voltage of the S.R. diode D_2 . Operations of these embodiments shown in FIGS. 9 and 10 can be readily understood on reference to the aforementioned embodiments.

What I claim is:

1. A pulse generator for producing unidirectional pulses comprising: pulse generation means having an output conductor,

a transfer impedance circuit transmissible of a dc current and having an input conductor and an output conductor, said input conductor being connected to the output of the pulse generation means, said transfer impedance including first and second series connected resistors having respective first leads connected together and respective second leads coupled respectively to said input and output conductors, and including a series connected combination of capacitor and a third resistor, said series connected combination being connected in parallel with one of said first and second resistors,

a step recovery diode one electrode of which is grounded and the other electrode of which is connected to the output conductor of the transfer impedance circuit,

a switching diode one electrode of which is connected to the output conductor of the transfer impedance circuit and another electrode of which is connected directly to a pulse generator output terminal,

means for causing a forward dc current to flow through the step recovery diode in the absence of a pulse from the pulse generation means,

whereby output pulses each having an extremely short rise time can be obtained at the output terminal as a result of the non-conduction and conduction, respectively, of the step recovery diode and the switching diode output pulse of the pulse generation means.

2. A pulse generator according to claim 1 further comprising an auxiliary switching diode having one electrode connected to the other electrode of the step recovery diode, said auxiliary switching diode having another electrode, and a dc source means for applying a dc voltage less than the inverse breakdown voltage of the step recovery diode to said other switching diode electrode.

3. A pulse generator according to claim 1, further comprising distributed constant circuit means inserted between the transfer impedance circuit and the said other electrode of the step recovery diode to improve the wave form of the output pulses.

4. A pulse generator according to claim 3, further comprising an auxiliary switching diode having one electrode connected to said other electrode of the step recovery diode, said auxiliary switching diode having another electrode, and a dc

source for applying a dc voltage less than the inverse breakdown voltage of the step recovery diode to said other switching diode electrode.

5. A pulse generator having an output terminal for producing uni-directional pulses comprising: pulse generation means having an output conductor,

transfer impedance circuit means transmissible of a dc current and having an input conductor and an output conductor, said input conductor being connected to the output of the pulse generation means for shaping the form of pulses produced by said pulse generation means, and for protecting said pulse generation means against excessive loads,

a step recovery diode one electrode of which is grounded and the other electrode of which is connected to the output conductor of the transfer impedance circuit means, a switching diode one electrode of which is connected to the output conductor of the transfer impedance circuit means and another electrode of which is connected directly to said pulse generator output terminal, means for causing a forward dc current to flow through the step recovery diode in the absence of a pulse from the pulse generation means,

distributed constant circuit means inserted between the transfer impedance circuit means and the said other electrode of the step recovery diode to improve the wave form of the output pulses, and an auxiliary switching diode having one electrode connected to the other electrode of the step recovery diode, said auxiliary switching diode having another electrode, and a dc source means for applying a dc voltage less than the inverse breakdown voltage of the step recovery diode to said other switching diode electrode,

whereby output pulses each having an extremely short rise time can be obtained at the output terminal as a result of the non-conduction and conduction, respectively, of the step recovery diode and the switching diode in response to an output pulse of the pulse generation means.

6. A pulse generator having an output terminal for producing uni-directional pulses comprising: pulse generation means having an output conductor,

transfer impedance circuit means transmissible of a dc current and having an input conductor and an output conductor, said input conductor being connected to the output of the pulses generation means for shaping the form of pulses produced by said pulse generation means, and for protecting said pulse generation means against excessive loads,

a step recovery diode one electrode of which is grounded and the other electrode of which is connected to the output conductor of the transfer impedance circuit means, a switching diode one electrode of which is connected to the output conductor of the transfer impedance circuit means and another electrode of which is connected directly to said pulse generator output terminal,

means for causing a forward dc current to flow through the step recovery diode in the absence of a pulse from the pulse generation means, and

an auxiliary switching diode having one electrode connected to said other electrode of the step recovery diode, said auxiliary switching diode having another electrode, and a dc source for applying a dc voltage less than the inverse breakdown voltage of the step recovery diode to said other switching diode electrode,

whereby output pulses each having an extremely short rise time can be obtained at the output terminal as a result of the non-conduction and conduction, respectively, of the step recovery diode and the switching diode in response to an output pulse of the pulse generation means.
